Specification for Design.

Patented Sept. 21, 1915.

Application filed May 14, 1915. Serial No. 28,218. Term of patent 14 years.

To all whom it may concern:

Be it known that I, FRED E. PAYNE, a citizen of the United States, residing at Middletown, in the county of Middlesex and State of Connecticut, have invented a new, original, and ornamental Design for a Rubber Boot, of which the following is a specification, reference being had to the accompanying drawing, forming a part thereof.

Figure 1 is a side elevation of a rubber boot, showing my new design. Fig. 2 is a

similar enlarged view of the foot and sole portion of the same. Fig. 3 is a view of the other side of the same. Fig. 4 is a bottom plan view of the same.

I claim:

The ornamental design for a rubber boot, as shown.

FRED E. PAYNE.
